DISPLAY EASEL

Application filed December 17, 1928. Serial No. 326,518.

This invention relates to means of easel type for displaying large sheets of advertising and the like. The type of display sheet to which reference is had comprises a rectangular flexible sheet of paper, cloth or the like, bearing on one face the matter to be displayed, the sheet being secured at opposite edges with stiffening strips by means of which the sheet may be stretched therebetween. Such a display sheet may, of course, conveniently be rolled upon one of its stiffening strips, for purposes of transportation.

The type of easel to which reference is made, is one adapted to engage the stiffening strips of the display sheet and stretch the sheet between them, as well as support one stiffening strip in a position to display the sheet dependent therefrom in upright position; and also adapted to be collapsed or knocked down to a form about which the sheet may be rolled for shipment.

The object of our invention is, therefore, to provide easel means of the class described which shall be of the simplest and cheapest construction and yet capable of functioning for the purpose set forth.

The exact nature of our invention together with further objects and advantages thereof will be apparent from the following description taken in connection with the accompanying drawings in which Fig. 1 is a perspective view from the rear quarter of apparatus in which an embodiment of our invention is incorporated, the apparatus being shown set up for display; Fig. 2 is a detail perspective view showing a portion of the display sheet removed from the easel portion of the apparatus; and Figs. 3 and 4 are views of the principal parts of our easel, Fig. 3 showing the parts included therein, in collapsed relation.

With reference now to the drawings, 1 is a sheet of paper, cloth or the like bearing on its reverse side not shown, the advertising matter or the like which is to be displayed. The sheet shown is rectangular and is secured at either end to stiffening members such as the rigid strips 2, 2a extending along the corresponding edges of the sheet. Thus the sheet may, by means of its end members 2, 2a, be stretched taut into a plane as shown Fig. 1

or may be limp between the end members as indicated Fig. 2. Obviously in the latter condition the sheet may be rolled to compact form as about one of the end members.

According to our invention we provide means in the nature of an easel, for supporting the sheet 1 in a substantially vertical plane as in Fig. 1 and for exerting tension between the members 2 and 2a for the purpose.

To this end we provide a post 3 comprising conveniently a base member having portions 3a and 3b with an insert member 3c removably securable therewith. The post is preferably of the knock-down form described in order that the longitudinal dimension of either part thereof be less than that of the strips 2. In the example shown the base member of the post is provided in its upper extremity with a socket 5 surrounded by a ferrule 6, the socket being adapted to receive the end of the insert 3c.

The member 2 is provided with a socket 7 adapted to receive the opposite end of the insert 3c to be supported thereby. Having at one end pivotal connection with the post as by the headed pin 8, is a supporting leg 9 whose free end may be stepped down as at 10 to seat and be supported in a socket in the member 2a similar to the socket 7 of the member 2. Arranged between the leg 9 and the lower portion 3a of the post 3, which thus forms the other of a pair of legs, is a member 11 adapted to control the stretch or opening between the legs. As shown the member 11 has resilient qualities obtained by the simple expedient of employing a rubber band for the purpose.

Thus as shown, Fig. 1, by arranging the parts as indicated and increasing the angularity between the leg 9 and the portions 3b and 3c of the post above the pin 8, the sheet 1 is stretched to taut condition, and by lowering the member 11 to prevent increasing the angle between the portion 3a of the post and the leg 9, such taut condition of the sheet 1 is maintained.

The insert 3c is preferably of wood or the like, and hence of some resilience, so that the same may be flexed when the sheet 1 is

stretched as indicated Fig. 1, whereby a tension is exerted between the members 2 and 2a. Under such conditions it is not essential that the member 11 be of resilient material since, for example, non-resilient connecting means would simply follow by gravity or could be forced downwards over the diverging legs of the supporting members until wedged thereupon. Thus a strip of fabric would serve nicely because of its frictional properties, maintaining its tightened position upon the legs. However, where the member 11 is resilient such as in the case of the rubber band the additional advantage of the tension between the legs assisting the tension in the member 3c is had.

The relative length of the post portion 3a, below the pin 8, is such that the lower extremity of the post will rest upon a floor or horizontal surface to maintain the taut sheet 1 upright and sloping slightly backwards from the vertical position. The apparatus as set up and as shown Fig. 1 has thus effectively a triangular base formed by the strip 2a and the lower extremity of the post, whereby the parts will be in stable equilibrium.

The parts may be disassembled as follows: The member 11 being slid upward, the legs 3a and 9 of the easel may be spread to relieve tension upon the strip 1, the strip members 2 released from the easel, the leg 9 swung to parallel relation with the leg 3a, the insert 3c removed from its socket. These members may then be placed together and secured by the tension member 11, and the limp sheet 1 rolled thereabout to form a compact bundle adapted to be nicely received in a mailing tube or the like; or the member 11 may be applied to secure the complete rolled bundle.

Obviously the reassembly may be accomplished by performing corresponding operations in the reverse order.

What we claim is:

1. In combination with a poster comprising a limp sheet extending between top and bottom end stiffening members, easel means for supporting said poster and comprising a post member having its upper end associated with the top poster end member and its other end adapted to rest upon a supporting surface, a leg member having one end pivotally connected with said post member intermediate the ends of the latter and its other end associated with the bottom poster end member, and endless means arranged about the easel parts below the pivot connection therebetween, to limit the angularity between said parts and thus tension the poster sheet between its end members.

2. In combination with a poster comprising a limp sheet extending between top and bottom end stiffening members, easel means for supporting said poster and comprising a post member having its upper end asso-

ciated with the top poster end member and its other end adapted to rest upon a supporting surface, a leg member having one end pivotally connected with said post member intermediate the ends of the latter and its other end associated with the bottom poster end member, and endless means arranged about the easel parts below the pivot connection therebetween, and adjustable on said parts, to limit the angularity between said parts and thus tension the poster sheet between its end members.

3. In combination with a poster comprising a limp sheet extending between top and bottom end stiffening members, easel means for supporting said poster and comprising a post member having its upper end associated with the top poster end member and its other end adapted to rest upon a supporting surface, a leg member having one end pivotally connected with said post member intermediate the ends of the latter and its other end associated with the bottom poster end member, and endless elastic means arranged about the easel parts below the pivot connection therebetween, to limit the angularity between said parts and thus tension the poster sheet between its end members.

In testimony whereof we hereby affix our signatures.
